UNITED STATES PATENT OFFICE.

HARRY W. SMITH AND CHARLES G. SMITH, OF PROVIDENCE, RHODE ISLAND, AS
SIGNORS TO NICKERSON ART METAL COMPANY, OF PROVIDENCE, RHODE ISLAND,
A CORPORATION OF RHODE ISLAND.

LINK-MESH MACHINE.

1,078,318.

Specification of Letters Patent. Patented Nov. 11, 1913.

Application filed April 5, 1913. Serial No. 759,179.

To all whom it may concern:

Be it known that we, HARRY W. SMITH and CHARLES G. SMITH, citizens of the United States, and residents of the city of Providence, in the county of Providence and State of Rhode Island, have invented certain new and useful Improvements in Link-Mesh Machines, of which the following is a specification.

This invention relates to machines for automatically making wire fabric of the type usually known as ring mesh, and consists of a multiplicity of links each inter-engaging with a plurality of other links, this invention being an improvement over that disclosed in our co-pending application Serial No. 626,954, filed May 13, 1911.

One of the objects of the invention is to provide improved means for controlling the feed of the mechanism which supports the fabric as it is being formed, said mechanism including a pair of pawl-engaged and cam-actuated rack-bars, and means in said bars for feeding said support but half a step at the beginning of each return movement.

A further object of the invention is to provide adjustable means in said bars whereby the position of the ratchet teeth may be adjusted relative to the operating pawls so as to accurately engage said pawls to feed the support half the diameter of a link at the beginning of each return movement.

A further object of the invention is to provide a pair of pawl-controlling bars and means for connecting said bars together whereby when one is moved to the operating position the other is moved to be inoperative.

With these and other objects in view, the invention consists of certain novel features of construction, as will be more fully described and particularly pointed out in the appended claims.

Of the accompanying drawings: Figure 1 is a plan view of the mesh-forming machine showing our improved mechanism attached thereto. Fig. 2 is a rear elevation of the machine showing the adjustable rack bars and actuating cams and the pawls, the pawl casing being in section. Fig. 3 is an enlarged view illustrating one of the pawls and its controlling cam bar in perspective. Fig. 4 is a plan view showing the edge of

the rack bars, the pawls and cam bars, the inner end of said cam bars being operatively connected through the reversing lever. Fig. 5 is a side elevation, partly in section, showing the carriage, the support for the fabric, and the carriage-actuating mechanism. Fig. 6 is a side elevation showing the adjustable eccentrically-mounted friction roll, in the end of the rack bar, whereby said bar may be adjusted longitudinally to set the fabric support with relation to the link forming tools. Fig. 7 is a plan view of the construction illustrated in Fig. 6 showing the screw for locking the adjusting eccentric after the bar has been set. Fig. 8 is a side elevation, partly in section, showing the reversing handle. Fig. 9 is a greatly enlarged view showing the general arrangement of the fabric links. Fig. 10 shows an enlarged view of the pawls and rack-bars illustrating the relative positions of the teeth after inserting the last link in a row. Fig. 11 shows the pawls as having been reversed and in position to be engaged by the other rack to cause the carriage to be moved one-half step at the beginning of the return stroke. Fig. 12 shows the relative position of the rack-bars after having moved the carriage one-half step to the right which is designated by the distance e between the center lines c .

The general construction of our present machine is the same as that fully illustrated and described in our above-mentioned co-pending application in which the table 30 of the machine is described as being provided with a bearing 31 for four shafts 32, 33, 34 and 35. The shaft 32 is provided with fast and loose pulleys 36, 37, the fast pulley having a crank or handle 38 by which the machine may be manually operated; and the four shafts are geared together by bevel pinions 39 so that they all rotate in unison. The bed 30 also supports a slide 40 on which is mounted the carriage base 41 having brackets 42 for the shaft 43 of the work-feeding pin-roll 44. Said roll may be an integral portion of the shaft, but is preferably a sleeve secured by set-screws 29. The pins 28 are all spaced to engage links of the fabric as clearly illustrated in Figs. 1 and 5. Suitably supported above and somewhat to the rear of the pin roll is a box 45 in which the roll of completed

fabric may be carried. This box is merely a convenience and may be replaced by any other suitable mechanism or device for receiving the work after it leaves the pin-roll. With such a box 45 in use, the operator simply occasionally takes up the slack of the fabric behind the roll 44 by revolving the roll of fabric in the box to wind up the fabric.

10 In Fig. 1 a reel 46 for the wire *a* that is employed to make the links, is shown as being suitably supported by a spindle 47. From said reel the wire is passed between upper and lower plates of a friction block 15 48 (Fig. 1), and is then passed to the feed device which may comprise any usual or suitable mechanism.

As more fully described and illustrated in the above-mentioned application the wire is 20 fed intermittently to the machine and is cut off and each piece then bent into a U-shape. The ends of this U are passed through adjacent links already formed in the fabric and then closed together by suitable means.

25 Our present invention consists in improved mechanism for controlling the feeding of the carriage step by step so that the successively formed rings or links will properly interengage with the previously formed 30 links in the margin of the fabric all of which mechanism is hereinafter fully described.

As shown in Figs. 1, 2 and 5 the box or casing 65 is secured to the carriage base 41, and contains two vertically movable pawls 66 and 66^a, which are normally pressed 35 downward by springs 67. Longitudinally slideable through this casing 65 and on the face of the carriage 41 is a pair of cam or pawl controlling bars 68 and 69 each having a downwardly extending end 70 and 71 respectively. The upper face of each of these bars is provided with a recess or notch 72 having inclined sides or faces and serve 40 the purpose of cams. The pawls 66 are provided with overhanging shoulders 73 each provided at their lower ends with beveled faces corresponding to the beveled or cam-shaped recess 72 which they are adapted to engage. As will be readily understood when a pawl has its shoulder in the recess it will be in engagement with its rack and when on the high portion of the bar it will be elevated to inoperative position. These bars 68 and 69 are provided 45 each with a pin 74 at their inner or forward ends which pins engage slots 75 in the shifting lever 76, said lever being pivotally connected to the carriage 41 by the center screw 76^a whereby when said lever is moved in one direction the said bars 68 and 69 are moved simultaneously in opposite directions 50 one to raise its pawl from engagement with its rack and the other to drop its pawl to operative connection with said rack. This

said lever is provided with a handle 77 whereby it may be manually operated for the purpose of shifting the direction of the carriage feed at the will of the operator and an adjustable pad 78 projects downwardly through said lever to engage the surface of said carriage for the purpose of retaining the lever in any desired position relative thereto. The position of these controller bars is automatically shifted at one 75 end of its travel by the engagement of the cam 79 with the end 70 of the bar 68 and at the other end by engagement of the cam 80 with the end 71 of the bar 69 whereby when one of these bars is moved inward by 80 contact with its cam the other is moved outward through the lever 76 to raise one pawl from engagement with its rack-bar and drop the other into engagement with the opposite rack-bar. These two rack-bars 81-82 85 as shown are provided with ratchet or saw-shaped teeth facing in opposite directions, that is, the teeth on one bar face in one direction and the teeth on the other bar face in the opposite direction, and are oppositely reciprocated through their bearings 83 and 83^a, one by the cam 84 and the other by cam 85, the return or outward motion being effected by the springs 90. The end of each rack-bar is preferably made in substantially a fork-shape, as illustrated in 90 Figs. 1 and 7, and between the branches of the fork is located a friction wheel 86 mounted on an eccentric center-pin 87. This center-pin has its bearing in the 100 branches of the fork and is retained in any desired position by means of the set-screw 88. When it is desired to adjust these bars longitudinally it is only necessary to release the screw 88 and by inserting a screw driver 105 into the slotted end 89 of the eccentric shaft the eccentric may be rotated so as to move the friction roller either inward or outward to adjust the teeth of one rack-bar relative to those of the other and thus position the 110 fabric relative to the forming tools.

In setting or timing up the machine the fabric support must be adjusted laterally relative to the operating position of this link forming mechanism, whereby the link 115 after having been formed into a U-shape may be passed through two or more adjacent links in the fabric. To bring this support into proper position requires a very fine adjustment. In some cases the pin roll 120 44 is moved longitudinally on its shaft 43 and then the finer adjustment is obtained relative to the operating pawls by adjusting one of the cam rolls in the ratchet bar to feed the carriage step by step. When the 125 carriage has reached the edge of the fabric it is necessary that when the pawls are shifted to engage the opposite rack-bar, the first feed of this carriage will be but half the length of a normal step. To effect this 130

the other rack-bar is nicely positioned by adjusting its cam roll and the carriage feeding mechanism is then ready for operation.

In the automatic operation of the machine 5 the shafts 32, 33, 34, and 35 are driven from the pulley 37 through a belt from any desired source of energy, and by rotating the cams 84 and 85 the ratchet bars 81 and 82 are reciprocated in opposite directions, but 10 since only one of the pawls 66 could be moved into operative position at a time the pawl casing 63 and the work carriage to which it is attached will be fed intermittently to the right until the cam 80 engages 15 the downwardly extending end 71 of the bar 68 and forces the same inward thus permitting the pawl shoulder which it engages to drop into the notch 72 and its pawl to engage the opposite rack and reverse the 20 operation of the machine.

Of course when a reverse of the carriage drive occurs at the end of its travel the pin roll 44 must be given a slight partial rotation to raise the row of links that have 25 just been completed a distance substantially equal to one-half the diameter of the rings or links, which is accomplished by means of the pawls 91 and 92 engaging the ratchets 93 and 94, respectively, at the proper time, 30 pawl 91 being actuated by the pin 95 in the cam 83 and pawl 92 by the pin 96 in the cam 84, all of which is fully described in the application above referred to.

In forming the fabric on our improved machine let it be understood that the link forming tools are relatively fixed and the fabric is moved laterally step by step and presented to receive the links from said tools. These links are inserted in the order 35 shown in Fig. 9, commencing at the left of the top row and working toward the right, the links are inserted from 1 to 5. Fig. 10 illustrates the position of pawl 66 as having been moved by its rack bar 81 in the direction of the arrow to move the fabric into 40 position to receive the last ring 5 of this first row. The fabric is then raised approximately one-half a link diameter and the positions of the pawls as shown in Fig. 1 45 are reversed, pawl 66^a being dropped into the path to be engaged with its rack bar. When this bar has completed the first half of its first step the pawl is then engaged by its tooth and the carriage moved a distance 50

55 equal to the last half of this step, thereby moving the fabric into position to receive ring No. 6. The position of pawl 66^a after this completed step is illustrated in Fig. 12, the carriage having been moved the distance 60 *c* relative to the center lines *c*. The rack bar 82 now continues to feed the carriage until the opposite margin of the fabric is reached and ring 10 is inserted when the fabric is again raised one-half a link and the rack 65 bar actuated to feed the carriage one-half

a step in the opposite direction into position to receive link 11 and so on the carriage is carried back and forth until the fabric is completely woven.

We claim:

1. In a machine of the character described, a support for a web of link mesh fabric, ratchet means for actuating said support to shift the fabric step by step, means for reversing the feeding action of said mechanism, and means in said actuating means for feeding said support but half a step in the feeding direction at the beginning of each return travel. 70

2. In a machine of the character described, a support for a web of link mesh fabric, ratchet bars, means for reciprocating said bars in opposite directions for actuating said support, means for reversing the feeding action of said bars, and means for controlling the action of said bars whereby the support is fed but half a step at the beginning of each return travel. 80

3. In a machine of the character described, a support for a web of link mesh fabric, ratchet bars, means for reciprocating said bars in opposite directions for actuating said support, means for reversing the feeding action of said bars whereby the support is fed but half a step at the beginning of each 90 return travel.

4. In a machine of the character described, a support for a web of link mesh fabric, a carriage on which said support is mounted, ratchet bars, cams for reciprocating said bars in opposite directions, pawls carried by said carriage for engaging said ratchet bar, means for controlling said pawls whereby the feeding action of said bars is reversed, and means for positioning said bars 100 for feeding said support but half a step at the beginning of each return travel.

5. In a machine of the character described, a support for a web of link mesh fabric, a carriage on which said support is mounted, 110 ratchet bars, cams for reciprocating said bars in opposite directions, pawls carried by said carriage for engaging said ratchet bars, cam actuated reciprocating controller bars for controlling said pawls whereby the feeding action of said rack bars is reversed, and means for positioning said bars for feeding said support but half a step at the beginning of each return travel. 115

6. In a machine of the character described, a support for a web of link mesh fabric, pawl and ratchet mechanism for actuating said support to feed the fabric step by step, a pair of cam actuated pawl controlling bars for moving said pawls into and out of engagement with said mechanism whereby the feed of said support may be reversed. 125

7. In a machine of the character described, a support for a web of link mesh fabric, pawl and ratchet mechanism for actuating 130

said support to feed the fabric step by step, a pair of cam-actuated pawl-controlling bars for moving said pawls into and out of engagement with said mechanism whereby the feed of said support may be reversed, and means whereby said bars may be manually actuated for reversing the action of the feeding mechanism.

8. In a machine of the character described, 10 a support for a web of link mesh fabric, pawl and ratchet mechanism for actuating said support to feed the fabric step by step, a pair of cam actuated pawl controlling bars for moving said pawls into and ~~out of~~ 15 engagement with said mechanism whereby the feed of said support may be reversed, and a pivoted lever connecting said bars whereby they may be manually actuated for reversing the action of the feeding mechanism.

20 9. In a machine of the character described, a support for a web of link mesh fabric, pawl and ratchet mechanism for actuating said support to shift the fabric step by step, a pair of cam-actuated pawl-controlling bars 25 for moving said pawls into and out of engagement with said mechanism whereby the feed of said support may be reversed, and means in said ratchet mechanism for feeding said support but half a step at the beginning 30 of each return movement.

10. In a machine of the character described, a support for a web of link mesh fabric, pawl and ratchet mechanism for actuating said support to shift the fabric step by 35 step, a pair of cam-actuated pawl-controlling bars for moving said pawls into and out of engagement with said mechanism whereby the feed of said support may be reversed, at the side margins of the fabric, and means 40 in said mechanism for adjusting the same whereby the support will be moved but half a step at the beginning of each reverse movement.

11. In a machine of the character described, 45 a support for a web of link mesh fabric, a carriage on which said support is mounted, ratchet bars, cams for reciprocating said bars in opposite directions, pawls carried by said carriage for engaging said 50 ratchet bars, cam-actuated reciprocating controller-bars for controlling said pawls whereby the feeding action of said rack-bars is reversed, and means for adjusting said 55 rack-bars longitudinally for feeding said support half a tooth at the beginning of each reverse movement.

12. In a machine of the character described, 60 a support for a web of link mesh fabric, a carriage on which said support is mounted, ratchet bars, cams for reciprocating said bars in opposite directions, pawls carried by said carriage for engaging said 65 ratchet bars, cam-actuated reciprocating controller-bars for controlling said pawls whereby the feeding action of said rack-bars

is reversed, and an adjustable eccentric in said rack-bars whereby they may be positioned to engage the pawls at the beginning of each reverse movement to feed the support half a step.

13. In a machine of the character described, a support for a substantially flat web of link mesh fabric, a carriage on which said support is mounted, ratchet bars having means for reciprocating them, pawls carried by said carriage for engaging said ratchet bars, and means for controlling said pawls to permit but one of them at a time to act, said means comprising a pair of controller bars having cam surfaces to shift 75 said pawls alternately into operative position.

14. In a machine of the character described, a support for a substantially flat web of link-mesh fabric, a carriage on which said support is mounted, ratchet bars having means for reciprocating them, pawls carried by said carriage for engaging said ratchet bars, and means for controlling said pawls to permit but one of them at a time to 80 act, said means comprising a pair of controller bars having cam surfaces to shift said pawls alternately into operative position, and means whereby said ratchet bars may be adjusted longitudinally to engage 85 the pawls at the beginning of each reverse stroke to move the support approximately half the diameter of a ring.

15. In a machine of the character described, a support for a substantially flat 100 web of link-mesh fabric, a carriage on which said support is mounted, ratchet bars having means for reciprocating them, pawls carried by said carriage and engaging said ratchet bars, a pair of controller bars pivotally connected together whereby both are actuated simultaneously to move said pawls, one into and one out of engagement with said racks, and means for actuating said 105 bars at opposite edges of the fabric to reverse the direction of travel of the carriage.

16. In a machine of the character described, a support for a substantially flat 110 web of link-mesh fabric, a carriage on which said support is mounted, ratchet bars having means for reciprocating them, pawls carried by said carriage and engaging said ratchet bars, a pair of controller bars pivotally connected together whereby both are actuated simultaneously to move said pawls one into 115 and one out of engagement with said racks, a cam for actuating said bars at opposite edges of the fabric to reverse the direction of travel of the carriage, and means in said ratchet bars for adjusting them longitudinally whereby said pawls will feed the carriage but half a step at the beginning of each return movement.

17. In a machine of the character described, a support for a substantially flat 120

- web of link mesh fabric, a carriage on which said support is mounted, ratchet bars having means for reciprocating them, pawls carried by said carriage and engaging said ratchet bars, a pair of controller bars pivotally connected together whereby both are actuated simultaneously to move said pawls one into and one out of engagement with said racks, a cam for actuating said bars at opposite edges of the fabric to reverse the direction of travel of the carriage, and means for manually operating said controller bars for reversing the travel of the carriage when desired. 30
- 5 19. In a machine of the character described, a support for a substantially flat web of link mesh fabric, a carriage on which said support is mounted, ratchet bars having means for reciprocating them, pawls carried by said carriage for engaging said ratchet bars, and a pair of controller bars, a pivoted manually operable lever connected to both bars whereby they are actuated simultaneously to move said pawls one into and one out of engagement with said rack, said lever having means whereby it may be retained in any desired position, and a cam for actuating one of these bars at opposite extremes of the carriage travel for operating said pawls and reversing the direction of said travel. 35 40
- 10 18. In a machine of the character described, a support for a substantially flat web of link mesh fabric, a carriage on which said support is mounted, ratchet bars having means for reciprocating them, pawls carried by said carriage and engaging said ratchet bars, a pair of controller bars pivotally connected together whereby both are actuated simultaneously to move said pawls one into and one out of engagement with said racks, a cam for actuating said bars at opposite edges of the fabric to reverse the direction of travel of the carriage, and means for manually operating said controller bars for reversing the travel of the carriage when desired. 45
- 15 20 25
- In testimony whereof we affix our signatures in presence of two witnesses. 50
